(57) **CLAIM**

The ornamental design for a cam for a rocker/recliner base, as shown and described.

DESCRIPTION

FIG. 1 is front, right, and top perspective view of a cam for a rocker/recliner base of the present invention;

FIG. 2 is a right plan view of the invention illustrated in FIG. 1;

FIG. 3 is a left plan view of the invention illustrated in FIG. 1;

FIG. 4 is a front plan view of the invention illustrated in FIG. 1;

FIG. 5 is a rear plan view of the invention illustrated in FIG. 1;

FIG. 6 is a top view of the invention illustrated in FIG. 1; and,

FIG. 7 is a bottom view of the invention illustrated in FIG. 1.

The broken lines in FIGS. 1-7 of the drawings illustrate portions of the cam for a rocker/recliner base that form no part of the claimed design.

1 Claim, 3 Drawing Sheets
